US00D621379S

(12) **United States Design Patent**
Song et al.

(10) **Patent No.:** US D621,379 S
(45) **Date of Patent:** ** Aug. 10, 2010

(54) **MOBILE PHONE**

(75) Inventors: **Han-Gil Song**, Seoul (KR); **Sang-Min Hyun**, Seoul (KR); **Chang-Hwan Hwang**, Goyang-Si (KR)

(73) Assignee: **Samsung Electronics Co., Ltd.** (KR)

(**) Term: **14 Years**

(21) Appl. No.: **29/345,418**

(22) Filed: **Oct. 15, 2009**

(30) **Foreign Application Priority Data**

Sep. 3, 2009 (KR) 30-2009-0039089

(51) **LOC (9) Cl.** 14-03

(52) **U.S. Cl.** ..... D14/138 R

(58) **Field of Classification Search** ..... D14/138 R, D14/138 AD, 138 AC, 138 C, 138 G, 191, D14/203.1–203.8, 496, 138 AA, 138 AB, D14/247–248, 137, 147, 218, 341–347; D10/65, D10/78, 104; D13/168; D18/7; 455/566, 455/575.1, 575.3

See application file for complete search history.
